UNIT ELECTRIC HEATER

Paul Petersen and Anton J. Markue,
Milwaukee, Wis.

Application January 9, 1952, Serial No. 265,582

5 Claims. (Cl. 219—19)

1

This invention relates to electric heating units such as portable heaters, and in particular a heating element which, in combination with a blower and air filter may be used as a furnace for residences, garages and the like or as a space heater for trailers and other enclosures.

The purpose of this invention is to provide means in combination with an electric heater for increasing the surface area whereby comparatively small heating elements are combined with fins so that the device functions as a furnace or similar heating unit.

Various types of electric heaters have been provided, however, heaters of this type have been used as auxiliary elements and because of the comparatively high cost of operation the electric heaters are not used as means for supplying basic heat for a residence, or other type of buildings. With this thought in mind this invention contemplates a method of combining a plurality of spaced fins with heating elements whereby the surface area of a body in which heating elements are installed is increased to such an extent that the device may be economically used as a furnace or the like.

The object of this invention is, therefore, to provide means for incorporating electric heating elements in a body having spaced fins extended therefrom whereby the fins increase the surface area so that the device operates efficiently as a heater.

Another object of the invention is to provide an electric heater in combination with a blower and filter whereby it is possible to provide a highly efficient electric furnace in a comparatively small housing.

A further object of the invention is to provide an electric heater adapted to be used as a furnace which is of a simple and economical construction.

With these and other objects and advantages in view the invention embodies alternately spaced comparatively thin plates with some of the plates having extended ends and wherein the plates are arranged in groups with electric heating elements positioned between the groups.

Other features and advantages of the invention will appear from the following description taken in connection with the drawings, wherein:

Figure 1 is a front elevational view illustrating the improved electric furnace.

Figure 2 is an end elevational view of the furnace.

Figure 3 is a vertical section through the furnace taken on line 3—3 of Figure 1.

Figure 4 is an elevational view on an enlarged

2

scale showing the heating element of the furnace with parts broken away and shown in section.

Figure 5 is an end elevational view of the unit shown in Figure 4.

Figure 6 is a detail illustrating one of the electric heating units incorporated in the heating element.

Figure 7 is a detail illustrating one of the plates forming the fins.

Figure 8 is a detail showing one of the spacers used between the plates.

Figure 9 is a view illustrating a wiring diagram adapted to be used with the furnace.

Referring now to the drawings wherein like reference characters denote corresponding parts the improved electric heater of this invention includes heating elements 10, plates 11, spacers 12, bolts 13 and 14 for retaining the plates, spacers and heating elements in assembled relation, a blower 15 actuated by a motor 16, a housing having a base 17, a front wall 18, a rear wall 19, a top 20, end wall 21 and a partition 22 having an opening 23 therein, and a filter 24 mounted on the partition 22 and positioned over the opening 23.

25 The heating unit as illustrated in Figures 4 and 5, may be used in different types of housings, such as in a furnace as a primary heater for a cottage or residence, or in a casing adapted to be used as a wall radiator for heating rooms, apartments and the like or as a space heater for trailers or similar vehicles.

As shown in the drawings the unit is formed with groups of plates as indicated by the numeral 11, with the plates separated by spacers 12 and the parts are assembled with the heating elements 10 which, as illustrated in Figure 4 are positioned between two of the spacers 12 and these are located between the groups of plates.

The plates 11 are provided with openings 25 and 26 through which the bolts 13 and 14 extend and similar openings 26 and 27 are provided in the spacers 12. The bolts pass through the openings in the plates and spacers and also extend through similar openings in bars 28 and 29 at the ends of the units. The nuts 30 and 31 on the ends of the bolts 13 and 32 and 33 on the ends of the bolts 14 provide means for positively clamping the elements in assembled relation. It is preferable to clamp the elements together with considerable force as the heating elements which are of the copper clad type have a tendency to burn out where they are not under pressure.

40 The heating elements are provided with extended tongues 34 and 35 which are connected to contact bars 36 and 37, respectively and the

50

contact bars extend to a switch box 38 in which switches 39 and 40 are positioned. The switch box is provided with an electric cord 41 having a plug 42 on the end thereof with which the unit may be plugged into a wall socket or the like.

The motor 16 is mounted on the base 17 of the housing through a support 43 and the fan 15 which is carried by the motor shaft is positioned to register with an opening 44 in a front wall 18 of the housing and in which a screen 45 is positioned.

The front wall of the housing is provided with an opening 46 over which a grill 47 is mounted and the air drawn inwardly by the fan 15 passes upwardly through the filter 24 in the opening 23 of the partition 22 and after circulating around the heating element, it is discharged through the opening 46.

The filter 24 is mounted in a frame 48 and the frame is secured to the partition 22 with bolts 49.

The contact bar 37 is connected to a source of current supply through the switch box 38 by a wire 50 and the bar 46 is connected to the opposite terminal of the source of supply through wires 51 and 52. The circuit of the blower motor 16 is connected to the wires 50 and 52 with wires 53 and 54, the switch 40 being positioned in the wire 54.

In the design shown, the heating element is supported above the filter 24 on the partition 22 with brackets 55, and it will be understood that the element may be supported by other suitable means.

With the parts formed in this manner air circulated around the heating element comes in contact with the extended ends of the plates 11 and with the plates heated by the heating elements 10 the temperature of the air is raised as desired. The heating elements may be formed of as many groups of plates as may be desired and the plates may be formed of various sizes.

Although it is preferred to form the plates and spacers of aluminum it will be understood that other suitable material or materials may be used.

It will also be understood that other modifications may be used in the design and arrangement

of the parts without departing from the spirit of the invention.

What is claimed is:

1. A portable electric heater comprising a group of plates of equal area, spacers of lesser area than said plates positioned between the plates of the group, and an electric heating element at one end of each of the group of plates and separated from said plate by a spacer, said plates having ends extended beyond the spacers and heating element.

2. A portable electric heater comprising groups of plates of equal area, spacers of lesser area than said plates positioned between the plates of the groups, flat heating elements positioned between each of groups of plates and separated from each group of plates by a spacer, said plates having ends extended beyond the spacers and heating elements, and means clamping the plates, spacers and heating elements in assembled relation.

3. A portable electric heater as described in claim 2 wherein the clamping means comprises bolts with nuts on the ends extended through the plates, spacers, and heating elements.

4. A portable electric heater as in claim 1 wherein means is provided for clamping the plates, spacers and heating elements in assembled relation.

5. A portable electric heater as in claim 4 wherein the clamping means comprises bolts with nuts on the ends extended through the plates, spacers and heating elements.

PAUL PETERSEN.
ANTON J. MARKUC.
